UNITED STATES PATENT OFFICE.

JOHN SCHUMER, OF CINCINNATI, OHIO, ASSIGNOR TO THE SCHUMER BROTHERS COMPANY, OF CINCINNATI, OHIO, A CORPORATION OF OHIO.

DESIGN FOR A FINGER RING.

Application filed October 12, 1927. Serial No. 23,734. Term of patent 7 years.

To all whom it may concern:

Be it known that I, JOHN SCHUMER, a citizen of the United States of America, and a resident of Cincinnati, in the county of Hamilton and State of Ohio, have invented a new, original, and ornamental Design for a Finger Ring, of which the following is a specification, reference being made to the accompanying drawing, forming a part thereof.

I claim:

The ornamental design for a finger ring as shown.

JOHN SCHUMER.
